UNITED STATES PATENT OFFICE.

JAMES H. GRAVELL, OF ELKINS PARK, PENNSYLVANIA.

NONRESOUNDING METAL VAT.

Application filed May 25, 1927. Serial No. 194,219.

This invention has for its object the provision of an improved metal vat useful for various purposes such for example as a container for washing machines.

- 5 It is one of the primary objects of the invention to provide a substantially sound-proof or non-resounding metallic container without using an excessive quantity of material in the production of the same.
- 10 It is a further object to provide a relatively strong and durable metal container which is resistant to corrosion both from the influence of the atmosphere or due to contact with the washing solutions to which it may be subjected.
- 15

The above objects are attained in the container disclosed herein without sacrificing any of the desirable features of this type of machine such as neatness of appearance, the 20 above and other objects appearing more fully from the following description when considered in connection with the drawings in which:

Fig. 1 is a sectional view of the members 25 forming the container assembled within one another.

Fig. 2 is a similar view of the completed vat disclosing one form of sealed edges.

Fig. 3 is a plan view of the device as shown 30 in Fig. 2.

Fig. 4 is a sectional view similar to Fig. 2 disclosing a different way of sealing the edges of the container.

In the present embodiment of the invention 35 the vat is formed of a series of seamless vat-shaped members 6 and 8 nested within one another and formed with an interlining 10 of the character described below. The outer member 6 is formed of a material having a 40 high tensile strength so as to give the requisite strength to the completed article, this member in the present instance being formed of sheet steel. The inner or intermediate member 8 is formed of a material possessing relatively 45 low tensile strength but substantially non-corrosive, such for example as copper or other like material, this member 8 being preferably of substantial thickness for producing the results described herein. The vat herein shown 50 is rectangular in shape although it will be understood that the same may be made circular or of any other desired shape.

The body members 6 and 8 are formed of graduated sizes as shown and are nested within 55 one another in intimate relation throughout the entire extent of the metal thereof to

form as near as practicable the equivalent of an integral one-piece vat. The two members 6 and 8 are preferably stamped together into their final form from two flat sheets of the 60 desired metal. It is accordingly considered desirable to coat the contacting surfaces of the two sheets of metal with a thin coating of lubricating oil to facilitate the simultaneous stamping of the metal and to effectively close 65 any space between the metals to exclude all moisture therefrom.

Under some conditions of use it is necessary to aperture the container as indicated for example at 12. All of the exposed edges 70 of the vat including the outer edge thereof and the edges adjacent the aperture 12 are effectively sealed to prevent the admission of any substance between the two container members 6 and 8. The sealing of the edges thus cooperates with the oil film between the members 6 and 8 to effectively prevent the formation of rust therebetween.

According to the form of the invention shown in Fig. 2 the edges are sealed by rolling the edges of the inner container 8 about the edges of the outer container 6 and, if desired, additionally sealing the final edges of the inner container where they extend over the edges of the outer container 6. In this form 80 of the invention the outer or upper edge of the container is formed with the rolled edge 14 and the apertured portion of the container is bent around as indicated at 16, the two flanges so formed, in addition to sealing the edges of the two container members, serving 85 also to reinforce or strengthen the exposed edges of the container.

The inner surface of the vat is covered by a nickel or other plating 10 covering all of the portion that is intended to be subjected to the washing solutions, the plating being applied only to the inner or intermediate member 8 of the vat.

According to the form of the invention 100 shown in Fig. 4 all of the exposed edges of the vat-shaped members 6' and 8' are sealed by means of an application of solder or other similar material for effectively preventing the seepage of any material between the two container members. There is accordingly supplied a body of solder 14' extending around the entire upper or outer edge of the vat and a similar body 16' extending around the aperture 12' in the base of the vat. The 105 members 6', 8', and 10' are formed of sheet steel, copper and nickel respectively, as in 110

the first form of the invention, the nickel plating in this instance preferably extending over the soldered portions 14' and 16' in order to enhance the appearance thereof.

5 This second form of the invention is desirable in that the two members 6' and 8' are effectively sealed together, the soldered edges presenting a smooth exterior surface free of extending parts which form substantially no obstruction to the use of any desired operating mechanism in connection with the vat.

10 It has been found that a vat or container constructed as above described is substantially dead or non-resounding thus producing the same effect as though a vat of much greater thickness were employed, but without the disadvantages thereof such for example as the additional weight and material 15 incident to a vat having a thicker wall. It is also found that a vat constructed as herein set forth possesses great strength, considerably greater than that of the outer steel casing 6 and further that the vat or container 20 is substantially rust proof since all of the surfaces exposed to the washing fluid are adequately protected by reason of the surface plating and the material of which the inner member 8 is formed.

25 30 The provision of the non-corrosive, intermediate member 8 (8') for receiving the inner coating or member 10 (10') possesses an additional advantage in that any defect in the inner lining 10 (10') will not result in a 35 rust spot but instead will merely permit the contents of the vat to have access to the copper member 8 (8') without any harmful effect. Furthermore a defect or opening in the lining 10 (10') can be readily patched or re-coated where this coating is formed upon the copper surface as herein disclosed.

40 Having now described my invention, what I claim and desire to secure by Letters Patent is:

45 1. A non-resounding metal vat for use with a mechanism of the washing machine type comprising a number of apertured vat-

50 shaped members of graduated sizes assembled within one another in intimate contact, said members being locally attached together at their rims and at the edges of the aperture therein.

55 2. A non-resounding metal vat comprising a number of vat-shaped members of graduated sizes assembled within one another, the outer member being formed of sheet steel, the intermediate member being of copper and the inner member being formed of nickel.

60 3. A non-resounding metal vat comprising a number of vat-shaped members of graduated sizes assembled within one another, the outer member being formed of a metal possessing relatively high tensile strength, the next member within said outer member being formed of a metal possessing relatively low tensile strength and the inner member forming 65 the inner surface of said vat being formed of a material capable of retaining a relatively high lustre.

70 4. In a washing machine, a vat-shaped member for association with the mechanism of said machine and comprising a non-resounding metal vat formed of a number of vat-shaped members of graduated sizes assembled within one another, the outer member being formed of a metal possessing relatively high tensile strength and the next member within said outer member being formed of a metal resistant to the effect of 75 corrosion.

80 85 5. A non-resounding metal vat for use with a mechanism of the washing machine type, comprising a relatively soft, rust-resistant vat-shaped inner member supported exteriorly by an outer sheet metal member embracing the side walls of said inner member and possessing relatively high tensile strength, said members being of substantial thickness and associated in intimate contact in the completed vat.

90 Signed at New York in the county of New York and State of New York this 23rd day of May A. D. 1927.

JAMES H. GRAVELL.
